CLAIM

The ornamental design for a hood cover with strap for a hair dryer, as shown and described.

DESCRIPTION

FIG. 1 is a front perspective view of a hood cover with strap for a hair dryer shown on a hair dryer hood in use or a person's head;

FIG. 2 is a front perspective view of the hood cover with strap for a hair dryer;

FIG. 3 is a side view;

FIG. 4 is a rear view;

FIG. 5 is a side view, showing the side opposite the side shown in FIG. 3;

FIG. 6 is a top view; and,

FIG. 7 is a bottom view.

The broken line showings of a hair dryer hood and person are for illustrative purposes only and form no part of the claimed design.
